UNITED STATES PATENT OFFICE.

WILLIAM A. VALENTINE, OF PHILADELPHIA, PENNSYLVANIA, ASSIGNOR TO EDWARD G. BUDD MANUFACTURING COMPANY, OF PHILADELPHIA, PENNSYLVANIA, A CORPORATION OF PENNSYLVANIA.

METHOD OF FITTING DIES.

Original application filed March 13, 1920, Serial No. 365,383, Patent No. 1,466,259. Divided and this application filed April 24, 1922. Serial No. 556,164.

My invention relates to an improved method of fitting dies and has to do, more particularly, with a method of fitting male and female dies such as are used in the manufacture of sheet metal stampings. This application is a division of my pending application for die fitting apparatus, Serial No. 365,383, filed March 13th, 1920.

Prior to my invention, it has been the practice especially in the case of large heavy dies to the fitting of which my present invention more particularly relates to rough form the dies and then to place a set of such rough-formed dies in the press in which they are to be used and bring the male and female dies into working relation to each other. The irregularities of surface and contour on the opposed faces of the die members are noted and the workmen grind, chip off, or otherwise remove and correct these irregularities while the dies are in the press, frequently bringing the dies into working relationship with each other to note the degree with which they approach a perfect fit. This practice is objectionable because it is very wasteful and inefficient. In the first place, the presses in which the dies are used do not have a long enough stroke to permit a separation of the dies materially greater than is necessary to insert a blank or sheet of metal between them. The result is that there is very little room for the workman to work in fitting the dies and when he has inserted the necessary tools it is difficult for the workman to watch the progress of the work and he is compelled to work in an awkward position. This makes the work of fitting the dies slow and tedious, adds materially to the cost of the fitting operation and makes it difficult to secure a perfect fit. Furthermore, the press is withdrawn from productive work and stands idle during the fitting of the dies and, since these presses are very costly machines, the fact that the press stands idle for a considerable period also adds materially to the cost of fitting dies by this method heretofore practiced.

The object of my invention is to provide a method of making or fitting dies in which the above-noted objections are eliminated in that the workmen are given plenty of room to enter between and work on the dies when fitting them and the dies can be fitted ready

for use outside of the press in which they are to be used, so that the latter does not have 55 to be withdrawn from productive work during the fitting operation.

Further objects, and objects relating to details and economies of operation, will 60 definitely appear from the detailed description to follow. In one instance, I accomplish the objects of my invention by the method described in the following specification. My invention is clearly defined and pointed out in the appended claims. A 65 method constituting a preferred embodiment of my invention is illustrated in the accompanying drawing, forming a part of this specification, in which:

Fig. 1 is a view in side elevation of a die 70 fitting apparatus illustrating one way of carrying out my invention.

In the drawing the same reference numerals refer to the same parts throughout the several views. 75

In general my invention consists in disposing the dies to be fitted in opposed relation, the one above the other, and bringing their die faces into surface contact with each other, but without pressure other than that 80 caused by the weight of the upper die resting on the lower die, in order to determine the surface irregularities which prevent a perfect fit of the two opposing die faces, then separating the dies a substantial distance 85 apart, that is, to a distance sufficient to accommodate the workmen and to permit them to enter the space between the separated dies to effect the removal or correction of any surface irregularities found to exist therein, 90 the dies being brought into contacting relation to each other as often as is desirable or necessary, during the fitting operation, for completing the determination and removal of the surface irregularities. The surface 95 irregularities of the dies may be determined by coating one or both of the mating die surfaces with paint or other coating material and noting the abrasion of such coat after the dies have been brought into contacting relation and then separated. I find it desirable to avoid the application of external pressure in bringing the mating die surfaces into contacting relation. This may be accomplished 100 in various ways, in accordance with my invention. According to one method, one of

the dies may be permitted freedom of movement relative to the other, that is, one of the dies may be suspended and lowered into contact with the mating die, so as to bear thereon by its own weight.

According to one method of carrying out my invention, the rough-formed dies, 10 and 11, are fitted with respect to each other by disposing them in opposed relation to 10 each other and suspending one of the dies so that it can be lowered into surface contact with the mating die. One or both of the mating surfaces of the dies, 10 and 11, are coated with a coat of paint and the 15 suspended die, 11, is lowered into gravity contact with the lower or fixed die, 10. The surface irregularities, indicated somewhat conventionally, at 12, are determined by noting the abrasion of the coated die surfaces 20 which may be observed after the dies have been separated. The dies, 10 and 11, are then separated a substantial distance apart, that is to a distance sufficient to accommodate the workmen and to permit them to 25 gain free access to the die surfaces for the purpose of removing or correcting the surface irregularities determined by observation of the abrasions of the coated surfaces. These irregularities may be removed or 30 corrected by the use of any suitable tools, such as the power driven chisel, 13, or the grinding wheel, 14, by manual operation, or by any other suitable tools and, in accordance 35 with my invention, the dies are separated so far apart that the workmen can get between them to operate these tools and observe the progress of the work, and the nature and extent of the irregularities to be corrected or removed.

40 I may suspend the die, 11, and lower it into gravity contact with the die, 10, to determine the fit and the surface irregularities or imperfections, and then raise the die, 11, a substantial distance to permit the 45 workmen to get at the dies. In order to facilitate the determination of the surface irregularities, it is desirable to avoid any excessive pressure and, with that end in view, I lower the die, 11, into gravity contact with the die, 10, and without the application of any external pressure, that is, die, 11, exerts no pressure on die, 10, other than that due to its own weight and the 50 weight of the member which carries it. In 55 the drawing, I have shown one illustrative form of convenient apparatus for handling the dies, while fitting them in accordance with my invention, which comprises a base, 16, on which the die, 10, is supported, and 60 a pair of spaced uprights or standards, 15, which are spaced a sufficient distance apart to allow plenty of room for the workmen to work on the dies. A carriage, 17, is mounted to slide on the ways, 18, provided 65 on the uprights, 15, and the die, 11, is se-

cured to the under side of the carriage in opposed relation to the die, 10. The carriage, 17, is suspended by the screw-threaded suspension rods, 19, on which work the nuts, 24. The said nuts are free to rotate, but are fixed against longitudinal movement on the rods, and are driven by shaft, 20, connected by pulley, 21, and belt, 22, to motor, 23. The lower ends of the rods, 19, extend freely through suitable openings 70 into recesses or chambers, 26, in carriage, 17, and have fixed heads, 25, in such recesses adapted to engage the upper walls thereof. This forms a suspending support for the carriage with a slip connection between the suspension rods, 19, and the carriage, 17, so that no external pressure is transmitted to the die, 11, and the rods serve merely to raise the carriage and the die and to permit the same to be lowered 80 into gravity contact of the die members, 11, 10. The motor, 23, may be of such construction that it will drive the belt, 22, in either direction at will, or a reversing gearing may be employed for reversing the direction of the drive. When the motor is driven, the shaft, 20, driving the nuts, 24, will cause the suspension rods, 19, to ascend or descend, raising or lowering the carriage, 17, and the die, 11. In my pending application for die fitting apparatus, Serial No. 365,383, filed March 13th, 1920, I have shown and claimed the apparatus, which I have just described generally, and in my pending application for die fitting 90 machines, Serial No. 365,384, filed March 13th, 1920, I have disclosed and claimed another form of apparatus which is adapted for handling the dies in carrying out the method of fitting dies disclosed and claimed 100 herein.

It is to be noted that, in accordance with my method of fitting dies, the dies are brought into surface contact with each other without the application of any substantial 110 external pressure. Consequently, the apparatus for handling the dies may be designed so as to provide plenty of room for the workmen to get at the die surfaces to work on them, since the apparatus does not have to be built to withstand heavy pressures such as are the rule in the presses in which the dies are used. One of the dies, for instance, 11, may be a master die and the other die, 10, may be fitted with respect to 115 this master, or both dies may be rough formed and then dressed in accordance with my invention until their mating surfaces fit perfectly with respect to each other. The dies, 10 and 11, may be brought into gravity 120 contact with each other as frequently as desired, during the fitting operation and then separated to renew the work on the die surfaces. The die surfaces may be brought 125 into actual contact with each other, to deter- 130

mine the surface irregularities, or they may be brought into contact with a sheet of metal of the thickness of the stampings to be formed by the dies, so that the die surfaces 5 are separated throughout by a distance equal to the thickness of the sheet of metal. I have used the terms "contact" and "contacting relation" in a sense including each of these conditions. In actual practice, I 10 find it practicable to fit the dies by bringing the die surfaces into actual contact. I find it convenient to coat the die surfaces in order to determine the surface irregularities but in some cases, the coating may be omitted and 15 the surface irregularities determined by noting the abrasions on the die surfaces themselves. After the dies are fitted in the manner above set forth, they are then placed in the power presses and operated in the 20 usual way. Thus it will be seen that the power presses are not required to be out of use while dies are being fitted together to replace those in use in the presses.

The process of my invention is of special 25 value in fitting together the surfaces of large and heavy dies such as are employed in shaping large sheet steel stampings. I do not desire, however, to be limited or restricted in this respect.

30 I am aware that the method disclosed in detail herein may be varied considerably and may be carried out in a wide variety of forms of apparatus, without departing from the spirit of my invention and, therefore, I 35 claim my invention broadly, as indicated by the appended claims.

Having thus described my invention, what I claim as new and useful and desire to secure by Letters Patent is:

40 1. The method of fitting dies which consists in disposing the dies with their mating surfaces in opposed relation to each other, bringing said surfaces into contact with each

other to determine the surface irregularities of one or both die surfaces, separating 45 said die surfaces a substantial distance apart to accommodate workmen in the intervening space, maintaining said dies in alignment throughout their relative movement, and removing said surface irregularities 50 while the die surfaces are so separated.

2. The method of fitting dies which consists in suspending one of said dies with its die surface in opposed relation to the die surface of the mating die, lowering said suspended die into contact with the other die to determine surface irregularities of one or both of said die surfaces, raising said suspended die to a substantial height to separate the die surfaces sufficiently to accommodate workmen in the intervening space, maintaining said dies in alignment during both lowering and raising operations, and removing the surface irregularities while 60 said die surfaces are so separated. 65

3. The method of fitting dies which consists in suspending one of said dies with its die surface in opposed relation to the die surface of the mating die, coating one or both of said die surfaces, lowering the suspended die into contact with the other die under pressure to determine surface irregularities, limiting said pressure to a value less than that of the working pressure of the dies, raising said suspended die so as to separate die surfaces a substantial distance apart to accommodate workmen in the intervening space, maintaining said dies in vertical alignment throughout said lowering and raising operations, and removing the 70 surface irregularities while said die surfaces are so separated. 75

In testimony whereof, I affix my signature.

WILLIAM A. VALENTINE.
